BY Henry C. Parker
ATTORNEY

UNITED STATES PATENT OFFICE

162,505

HANDLE FOR FURNITURE

Joseph Adkinson, York, Pa., assignor to Home
Furniture Co., York, Pa., a corporation of Pennsylvania

Application October 28, 1949, Serial No. 5,755

Term of patent 3½ years

(Cl. D10—8)

To all whom it may concern:

Be it known that I, Joseph Adkinson, a citizen of the United States, residing at York, Pennsylvania, have invented a new, original, and ornamental Design for a Handle for Furniture, of which the following is a specification, reference being had to the accompanying drawing, forming a part hereof.

Fig. 1 is a perspective view of a handle for furniture, showing my new design,

Fig. 2 is a plan view of the handle,

Fig. 3 is an elevational front view of the handle, while

Fig. 4 is a side view of the handle.

I claim:

The ornamental design for a handle for furniture as shown.
